UNITED STATES PATENT OFFICE.

DANIEL G. REITZ, OF BERLIN, PENNSYLVANIA.

DUST-COLLECTOR.

SPECIFICATION forming part of Letters Patent No. 415,368, dated November 19, 1889.

Application filed April 27, 1889. Serial No. 308,849. (No model.)

To all whom it may concern:

Be it known that I, DANIEL G. REITZ, a citizen of the United States, residing at Berlin, in the county of Somerset and State of Pennsylvania, have invented a new and useful 55 Dust-Collector, of which the following is a specification.

This invention relates to dust-collectors for mills of that class which are operated by an 60 air-blast from a suction-fan; and it has for its object to provide a device of this class which shall be simple in construction, durable, and efficient in operation.

With these ends in view the invention consists in the improved construction and arrangement of parts, which will be hereinafter 65 fully described, and particularly pointed out in the claims.

In the drawings hereto annexed, Figure 1 is 70 a perspective view of my improved dust-collector, parts of the same having been broken away for the purpose of showing the invention more clearly. Fig. 2 is a vertical sectional view. Fig. 3 is a horizontal sectional 75 view taken on the line $x-x$ of Fig. 2. Fig. 4 is another horizontal section, but taken through the tangential opening.

The same letters refer to the same parts in all the figures.

30 The casing of my improved dust-collector consists, mainly, of a funnel-shaped hopper A, the upper edge of which is provided with a laterally-extending flange B.

C is a cylindrical shell, of a diameter corresponding to that at the upper edge of the hopper and provided at its lower edge with a flange D, which is suitably connected to the flange B of the hopper A by means of bolts or rivets. The upper edge of the cylindrical 40 shell C is likewise provided with a flange F, to which the top or dome G is bolted or otherwise suitably attached. The cylindrical shell C is provided with a tangential opening H, which is to be connected by means of suitable 45 pipes or ducts with the discharge-opening of a suction-fan, which latter is in turn to be connected with the rooms from which the impure or dust-laden air is to be taken. This fan and its connections, however, have not been shown 50 in the drawings hereto annexed, as their relative arrangement is well understood.

I designates an interior funnel-shaped hopper, the upper edge of which is suitably connected with the upper edge of the exterior hopper or casing A, but the lower end of which terminates in an opening J some distance above the discharge-opening K at the lower end of the exterior funnel or casing A. It will thus be seen that a space L is left between the walls of the two hoppers, the purpose of which will be presently made clear. 55

The inner funnel-shaped hopper I is provided with several circumferential series of slits or openings M M, adjoining which are formed flanges N N, which may be struck up 60 from the metal of which the said funnel or hopper is composed, and which are formed on the sides of the slits or openings I toward which the blast of air is directed. It will thus be seen that the said flanges form ledges 65 upon which the dust may lodge, and from which it will be discharged through the slits or openings next below or through the bottom opening K into the exterior shell or casing A. With this end in view it will also be seen 70 that the slits or openings of each circumferential series are arranged at an angle or inclination to those in the series next below. From the flanges or ledges of the lowermost 75 series the dust will be discharged directly 80 through the opening J at the bottom of the funnel-shaped shell I into the outer shell A, from whence the dust is eventually removed through the opening K at the bottom of the same. 85

The top or dome G of the device has a central opening O, to which is attached a downwardly-extending cylindrical tube P, which extends any desired distance into the interior funnel-shaped shell I, as will be seen in Fig. 90 2 of the drawings. This cylinder forms a deflector for the blast of air as it enters the upper cylindrical casing, and also serves for the escape of the purified air. When the impure or dust-laden air enters the upper cylindrical 95 casing C, it is deflected by the cylinder P and caused to circulate downwardly into the inner shell or hopper I, where it circulates in a rapidly-revolving current. The particles of dust and other impurities contained in the air will 100 by the centrifugal action of the air-current be thrown into contact with the wall of the fun-

nel-shaped hopper I, where the said dust will be intercepted and caused to lodge against the flanges or ledges N, from whence it will be deflected either through the slits M or through 5 the opening J into the exterior hopper or casing, from whence it is finally discharged through the opening K. The air, having been relieved of the dust and impurities, escapes through the tube P.

10 Having thus described my invention, I claim—

1. In a dust-collector having a tangential inlet, the combination of an outer shell or casing, an interior funnel-shaped hopper provided with interiorly - arranged inclined flanges or ledges, and slits or openings adjoining the same and having an opening at 15 the bottom, substantially as herein described, and for the purpose set forth.

2. In a dust-collector having a tangential inlet, the herein-described funnel-shaped hopper, arranged within a suitable casing and provided with circumferentially - arranged slits or openings, and struck-up flanges or ledges adjoining the same on the side from 20 which the air-blast is directed, substantially as and for the purpose herein set forth.

3. In a dust-collector having a tangential inlet, the combination, with an exterior funnel-shaped shell or casing, of an interior funnel-shaped hopper attached to the upper edge of 25 said shell or casing and terminating at some distance above the bottom of the latter, whereby an annular space or compartment is formed between the said casing and hopper, said inner hopper being provided with flanges to intercept or gather the dust and convey it into 30

35

said annular space or compartment, substantially as herein described, and for the purpose set forth.

4. In a dust-collector having a tangential inlet, the combination, with an exterior funnel-shaped casing, of the interior funnel-shaped hopper attached to the upper edge of 40 said casing and terminating at some distance from the lower end of said casing, said hopper being provided with circumferentially - arranged slits or openings and having struck-up ledges or flanges adjoining said openings, substantially as and for the purpose set forth.

5. In a dust-collector, the combination of the funnel-shaped casing and the interior funnel-shaped hopper connected at their upper edges, 45 said shell and hopper having openings at their lower ends and the interior hopper being provided with circumferentially-arranged slits or 50 openings, and struck-up ledges or flanges adjoining the same, with the cylindrical casing attached to the upper edge of the funnel-shaped shell and having a tangential opening 55 for the admission of dust-laden air, and a deflecting and escape tube extending downwardly from the top of said cylindrical casing, substantially as and for the purpose herein set forth.

In testimony that I claim the foregoing as my own I have hereto affixed my signature in presence of two witnesses.

D. G. REITZ.
